Attorney

UNITED STATES PATENT OFFICE

RALPH HAMILTON BEACH, OF ROYAL OAK, MICHIGAN, ASSIGNOR, BY MESNE ASSIGNMENTS, TO INTERNATIONAL RADIATOR CORP., OF PORT CHESTER, NEW YORK, A CORPORATION OF NEW YORK

TEMPERATURE-CHANGING UNIT

Application filed July 22, 1927, Serial No. 207,755. Renewed October 9, 1929.

My invention relates to improvements in heating units and is more particularly directed to that type of unit wherein a heating medium is used for increasing the temperature of a room or the like.

The object of my invention is to provide a heating system wherein the elements used therein for distributing the heat are constructed in a simple and efficient manner, and more particularly embodies the main features disclosed in my copending application filed January 31, 1927, and bearing Serial No. 164,947.

The invention as set forth in this application includes a heating unit which is composed of a plurality of pipes having thereon fins, the pipes serving to conduct a heating medium, while the fins are adapted to conduct the heat from the pipes and are so positioned that circulation of air thereabout will carry off heat from the fins.

The principal object of the present invention is to provide a unit of the type described which is composed of a series of flattened pipes and which are connected by suitable connections of the type hereinafter described and which constitute the salient points of this application.

Still another object of my invention is to provide a special fin which is adapted to be secured to the exterior of a flattened pipe to conduct therefrom the heat which may be within the pipe.

With these and other objects in view, the invention consists in a general arrangement and combination of parts which will be hereinafter more fully described in the following specification and specifically set forth in the appended claims when taken in conjunction with the accompanying drawings, in which

Figure 1 is a side elevation of my improved heating unit.

Figure 2 is a plan view illustrating the type of fin employed.

Figure 3 is a side elevation of the fin disclosed in Figure 2, and

Figure 4 is a view showing in perspective the various forms of my improved connections.

Referring to the accompanying drawings

in detail wherein like reference characters denote corresponding parts throughout the several views, the numeral 1 indicates in general a heating unit which is composed of one or more sections, each section being connected to a common supply pipe indicated by the numeral 2.

As disclosed in Figure 1, the heating unit is composed of a plurality of pipe sections 3, each section being formed of a flattened tube and spaced apart from each other and connected to the common supply pipe 2 by suitable connections which I will hereinafter more fully describe.

As disclosed in Figure 4 wherein I have illustrated the various embodiments of my invention, it will be noted that I have provided a T connection 4, the leg 5 of which is internally threaded and receives therein the supply pipe 2. The legs 6 and 7 which are arranged at right angles to the leg 5 are likewise internally threaded and receive therein the threaded end of a nipple 8 which serves to connect to the T 4 either of the legs 9 or 10. The T 4 is further provided with an elongated opening 11 which is formed, integral therewith and is so positioned with respect to the body 4 of the T that its face projects outwardly from the peripheral face of the body 4. The opening 11 receives therein the end of a pipe section 3 and when this pipe section 3 is positioned therein a suitable connection is formed by welding or any other desired method. As disclosed in Figure 1, the nipple 8 has connected thereto the connection 9 which is likewise formed with a cylindrical body 12 which is interiorly threaded to receive the end of the nipple 8 and is further provided with an elongated opening 13 which receives therein one end of the flattened pipe 3.

The other nipple 8 has connected thereto the connection 10 which is formed in a manner similar to both 4 and 9, but is further provided with an opening 14 which receives therein either a nipple similar to those hereinbefore mentioned for increasing the number of pipe sections or for the reception of a plug 15 which may be removed to withdraw

from the unit condensation which has taken place.

It will be noted from the drawings that each of the connections 4, 9 and 10 is provided with a sloping wall passing from the upper portion of the elongated opening and falling back into the body of the connection, thus presenting a gradual slope from one part of the flattened pipe to the cylindrical body of the connection.

10 Each of the pipe sections 3 has positioned thereabout and spaced equidistant thereapart a plurality of heating radiating fins 16, each of which is formed of metal, either 15 by casting or stamping from heavy sheet metal and preferably of rectangular shape, as illustrated in Figure 2 of the drawings. The central portion of the fin 16 is provided with an opening 17 and a flange 18 adjacent the 20 opening, the latter receiving therein the pipe 3 and when the fin is properly placed upon the exterior of the pipe, it may be permanently secured thereto by welding or the like. The fin 16 is further provided with a series 25 of channels 19 which extend about the pipe 3 and serve to increase the area of heat radiating surface and to stiffen the fin.

Having thus fully described my invention it will be clearly apparent that when a heating unit is constructed in accordance with the structure disclosed in Figure 1 that by reason of the flattened surface of the pipe sections cold air engaging the lower end or edge of the section will pass up and around 35 the section as illustrated in Figure 1, thus remaining in contact with the pipe section a greater length of time and thereby insuring a greater heating radiation than in devices wherein a cylindrical pipe section is employed. Furthermore, by reason of the 40 specific connection which I have employed and by slightly inclining the pipe section 3, condensation which occurs within these sections may readily pass back into the line of supply.

45 From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

50 1. A heating unit of the class described composed of a flattened radiating tube and a supply pipe, and a connection between the tube and pipe having a passageway whose lowest point of drainage is below that of 55 the passageway of the pipe at the point of

connection, thereby preventing the accumulation of condensation in the tube.

2. In a heating unit of the class described, the combination of a series of flattened radiating tubes and a supply pipe, a connection for forming communication between the tubes and the pipe, said connection having an offset inclined portion within which the tube end is received, and said offset portion directing condensation from the tube 75 into the supply pipe.

In testimony whereof I affix my signature.

RALPH HAMILTON BEACH.
